ILLUMINABLE CHRISTMAS ORNAMENT

Otto Kadmon and Alice Kadmon, both of 144—37 76th
Road, Flushing, N.Y. 11367

Filed May 31, 1966, Ser. No. 2,491

Term of patent 7 years

(Cl. D29—1)

The essential features of the design reside in the portions shown in solid lines, the conventional cord and plug being shown in broken lines.

We claim:

The ornamental design for an illuminable Christmas ornament, substantially as shown and described.
